(57) **CLAIM**

The ornamental design for a candle, as shown and described.

DESCRIPTION

FIG. 1 is a perspective view of the candle;

FIG. 2 is a top plan view of the candle;

FIG. 3 is a bottom plan view of the candle;

FIG. 4 is a side elevational view of the candle; and,

FIG. 5 is a sectional view of the candle along the line 5—5 of FIG. 4.

The broken line showing of the wick is for illustrative purposes only and forms no part of the claimed design.
